LIQUID APPLICATOR

Frederick W. Bryant, Hanover, N. J.

Application July 16, 1946, Serial No. 683,953

1 Claim. (Cl. 15—134)

This is a continuation in part of my application filed July 18, 1945, Serial No. 605,772, now abandoned.

The invention relates to a liquid applicator, and it consists in the constructions, arrangements and combinations herein described and claimed.

It is the cardinal object of the invention to provide a liquid applicator wherein the applicator carrier element will quickly absorb a measured quantity of liquid so that no liquid other than that absorbed by the carrier will remain in the applicator.

It is also an important object of the invention to provide an extremely absorbent carrier material so as to take up and hold by its own power of capillary attraction, such liquid as may constitute the carrier's capillary potential in order that the holding power of said material shall prevent drippage and leakage.

It is a still further object of the invention to provide a holder and applicator carrier element of a capacity so that when said carrier element is introduced into a receptacle containing a liquid, a full and complete saturation is obtained in readiness, without danger of subsequent leakage of liquid, for transfer to desired surfaces.

More specifically, it is an object of the invention to provide a novel construction of instrument in which a tubular liquid-receiving receptacle is adapted to frictionally yet releasably secure a sleeve therein, the latter having slots extended through the major portion of its length, the sleeve having a carrier holder detachably mounted in the outer end thereof, the holder being tubular for reception of a carrier of high absorption qualities, of a length so as to project beyond the open end of the holder and into said sleeve and occupy a position substantially the length of said slots, whereby upon initial insertion of the sleeve and carrier within the receptacle, a rapid absorption of the liquid will be inherent without liability of spillage, after absorption.

Additional objects, advantages and features of invention will be apparent from the following description and accompanying drawing, wherein

Figure 1 is a vertical sectional view showing certain of the parts in separated positions,

Figure 2 is a perspective view illustrating the manner of filling the applicator,

Figure 3 is a view in section and elevation illustrating the operative position of the parts,

Figure 4 is a view similar to Figure 1 illustrating a modified form of the device.

2

There is illustrated an applicator generally indicated by the reference character 10 consisting of a liquid-receiving receptacle 11 of tubular conical shape within which there is frictionally yet releasably seated as shown in Figure 3, a sleeve 12, which functions as a support for a carrier holder 13, as will be explained in detail hereinafter. The sleeve 12 is tubular and conically shaped corresponding to the receptacle 11, the upper end being enlarged circumferentially as at 14, forming an annular shoulder 15 adapted to seat upon the upper open end of the receptacle 11 when in operative position. The enlarged portion 14 has formed upon the inner periphery thereof an annular seat 16 concentric with the inner periphery of the sleeve 12, which functions as a connecting means for the carrier holder 13 as will now be described.

The holder 13 is of cylindrical tapered form, one end 17 being of a diameter to fit within the open end of the sleeve 12. The end 17 is provided with circumferentially spaced ribs 18 to frictionally engage the seat of the sleeve.

The outer end of the holder is cut away as at 19 providing a cuticle working instrument 20 of generally spoon shape, although the outer end may be otherwise shaped. In addition, the instrument affords a back support for a liquid carrier, as will be apparent as the description proceeds.

The sleeve 12 has a bottom wall 21 and extending upwardly therefrom, a plurality of circumferentially spaced slots or openings 22 are formed in the wall thereof; these slots extend the major length of the sleeve and preferably terminate at points slightly below the shoulder 15. The wall 21 may also be formed with an opening 22' (Fig. 3). The slots and opening perform an important function when filling a liquid carrier, as will be explained.

A liquid carrier or applicator 23 is disposed within the holder 13, which initially is of a diameter less than the passage through the holder so that it may be inserted through the opening at the end 17 and adjusted as to the amount which shall project at the working instrument 20, which will vary according to different needs, as will be apparent. With the carrier 23 positioned in the holder and projecting from the lower end thereof, the sleeve 12 is applied to the end 17 so as to fully seat the holder.

Liquid to be employed in the instrument is now poured into the receptacle 11 substantially to the upper open end thereof, only sufficient clearance being allowed for presentation of the bottom wall

21 of the sleeve, as best seen in Figures 1 and 2. The sleeve 12 being moved downwardly into the receptacle the level of the liquid will be raised so as to find passage through the opening 22' and slots 22 and into absorption relation with the carrier 23. The carrier is formed from a synthetic sponge material of cellular structure having a high value of absorption, so that the carrier quickly absorbs the liquid and by reason of its cellular structure expands so as to snugly engage within the holder. The sleeve 12 when finally seated within the receptacle 11 will be amply retained therein by reason of the large contacting surfaces between the sleeve and the receptacle and the further reason that a vacuous condition will be inherent in the receptacle 11.

In the forms shown, the instrument is admirably suited for applying a cuticle softening liquid to a person's finger nails, by merely presenting the end 24 to the nail and applying a light pressure whereupon the liquid will be discharged from the carrier. Obviously, the device may be employed in other situations, such as for instance, applying a liquid dye to the hair, eye lashes and brows; applying a liquid to the lips of a user, or may be employed for applying a perfume to a person.

In Figure 4, a modified form of the device is shown, the parts being identical with the structure just described, except that the sleeve 12' is of short length and open at the bottom so as to expose the major portion of the carrier 23'.

In order that the device may be carried upon the person or in a purse or the like, a closure cap 25 is provided, of a length to readily receive the holder 13 therewithin and having an interior shape complementary to that of the holder and preferably having a slight frictional fit thereupon. The diameter of the open end of the cap 25 is such as to snugly abut upon the enlarged portion 14 of the holder thus providing a smooth exterior contour.

It will be noted that by providing openings or slots 22 of elongated form, a substantial portion of the absorbent material is exposed to the 45

air at the time of filling permitting quick and complete absorption of a liquid, without liability of spillage thereof.

While I have shown and described preferred forms of the device, this is by way of illustration only, and I consider as my own all such modifications in construction as fairly fall within the scope of the appended claim.

I claim:

10. A liquid applicator comprising a cylindrical carrier holder having open ends, a liquid carrier normally loosely fitted within said carrier holder, a portion of said liquid carrier projecting at one end of the carrier holder, with the major portion thereof projecting from the opposite end of the carrier holder, a sleeve detachably connected to said carrier holder loosely receiving the major portion of said liquid carrier, said sleeve having circumferentially spaced slots disposed longitudinally of said sleeve and extending from a point closely adjacent the lower end of the sleeve to a point above the major portion of the liquid carrier within the sleeve, and a liquid receptacle complementary to and receiving said sleeve, said 20 liquid carrier being of extremely high absorptive quality whereby upon initial and subsequent insertion of the sleeve within the liquid of the receptacle, said liquid carrier will accept and hold the amount of liquid within said receptacle.
25. 30.

FREDERICK W. BRYANT.
